VARIABLE-INDUCTANCE COIL HAVING CORE
THREADED IN COIL FORM
Hisao Maeda, 13 Shiba-koen, Minato-ku,
Tokyo-to, Japan
Filed May 24, 1960, Ser. No. 31,376
Claims priority, application Japan May 25, 1959
3 Claims. (Cl. 336—136)

This invention relates in general to variable inductors and in particular to a new and improved assembly of a hollow bobbin and a ferrite core for variable-inductance coils.

It is an object of this invention to provide a bobbin for variable-inductance coils wherein the disadvantages inherent in conventional bobbins of this type, as will be described hereinafter, have been eliminated.

It is another object of the invention to provide a bobbin for variable-inductance coils, employing movable ferromagnetic core slugs, which has a simple, yet strong, construction adaptable to and reproducible in mass production with a high degree of uniformity.

The manner in which the foregoing as well as other objects and advantages may be best achieved will be understood more fully from a consideration of the following description of one representative embodiment of the invention, taken in conjunction with the accompanying drawing in which:

FIG. 1 is an elevational view, in longitudinal section, of a bobbin embodying the invention;

FIG. 2 is a cross-sectional view of the bobbin of FIG. 1 having a wedge member attached to it;

FIG. 3 is an elevational view of one example of a ferrite core to be fitted into the bobbin of FIGS. 1 and 2;

FIG. 4 is a plan view of the core of FIG. 3; and

FIGS. 5a and 5b are a perspective and a cross-sectional view of the wedge member of FIG. 2, the latter being taken along the line VB—VB of FIG. 5a.

In FIG. 1, the hollow bobbin cylinder or coil form 1 of the embodiment is made of a hard insulation material such as a hard synthetic resin and has one or more slots 2 cut in the longitudinal direction. Said slots 2 are adapted to receive the shank portion of one or more wedge-shaped bodies 3 which are made of a substance such as styrene, vinyl chloride, or other relatively soft insulating material, and which are provided with integrally formed flanges 4 of curved configuration and relatively reduced thickness for intimately contacting the outer surface of the bobbin cylinder 1. The member 3, or each of several such members, has a shank 3' adapted partly to protrude into the interior of the bobbin cylinder 1 upon insertion and to be held firmly thereto by the coil C wound about the bobbin cylinder 1.

In assembling the bobbin of the invention with an inductance-adjusting ferrite core Fe shown in FIGS. 3 and 4, the said core Fe is screwed directly into the bobbin interior, the outer screw threads of the core Fe thus cutting into and tapping the pliable, wedge-shaped member or members 3, whereby an extremely firm fitting is obtained between the mating parts.

The bobbin of this invention enables inductance adjustments to be made by causing the ferrite core Fe to move within the bobbin interior through the action of conventional threads on the outer surface of the said core. This bobbin has the further advantage of tight fit even if a certain dimensional difference exists between the inner diameter of the bobbin cylinder 1 and the outer diameter of the core Fe because the wedge-shaped member or members 3 have pliability. Moreover, it is possible to obtain a higher Q value than in the conventional core wherein a metal screw is used because the inner

2

diameter of the bobbin cylinder 1 can be made closer to the outer diameter of the core Fe.

Furthermore, the bobbin of the invention has the advantage of being easily fabricated, there being no necessity of carrying out the difficult process of cutting precise screw threads on the inner surface of the bobbin cylinder made of hard insulation material, and there being only the necessity of cutting a slot, or slots, 2 in the bobbin cylinder 1 in the longitudinal direction. It is a special feature of the invention that, since the flange 4 of the member 3, on the outer surface of the bobbin cylinder 1, is held fast by the coil C wound about the said bobbin cylinder, the member 3 is fastened securely to the said bobbin cylinder, and the core Fe yieldably but positively engaged thereby is held securely in its selected axial position relative to the coil whereby stability of operation is insured.

Although this invention has been described with respect to a particular embodiment thereof, it is not to be so limited as changes and modifications may be made therein which are within the full intended scope of the invention, as defined by the appended claims.

What I claim is:

- 25 1. A variable-inductance coil comprising a tubular coil form of relatively hard electrically insulating material provided with at least one longitudinal slot, a body of relatively soft electrically insulating material engaging said slot and projecting therethrough into the interior of said form, said body having a flange thereon positively engaging said form and being held against inward radial displacement by said flange, said flange extending generally parallel to the axis of said form while overlying the periphery thereof, wire-coil means wound around the periphery of said form and said flange, thereby securing said body in said slot, and a core threaded into the interior of said form in engagement with said body.
- 30 2. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 35 3. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 40 4. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 45 5. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 50 6. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 55 7. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body.
- 60 8. A variable-inductance coil comprising a tubular coil form of relatively hard electrically insulating material provided with at least one longitudinal slot, a generally T-shaped body of relatively soft electrically insulating material having a shank portion engaging said slot and projecting into the interior of said form therethrough, said body further having a flange portion engaging the periphery of said form and held against inward radial displacement therein, wire-coil means wound around the periphery of said form and said body, thereby securing said body in said slot, and a core threaded into the interior of said form in engagement with said body, said flange portion bearing externally upon said form and having a thickness substantially less than that of said form.
